[57] CLAIM

The ornamental design for a table leg structure for supporting
glass tops of a table, as shown and described.

DESCRIPTION

FIG. 1 is a perspective view of a table leg structure for supporting glass tops of a table, showing my new design; FIG. 2 is a front elevational view thereof, with the broken lines showing the glass tops of the table for environmental purposes only and forming no part of the claimed design; FIG. 3 is a rear elevational view thereof, with the broken lines showing the glass tops of the table for environmental purposes only and forming no part of the claimed design; FIG. 4 is a bottom view thereof; FIG. 5 is a top view thereof; FIG. 6 is a left side elevational view thereof; and, FIG. 7 is a right side elevational view thereof.
